CLAIM

The ornamental design for a motor vehicle and/or toy vehicle replica, as shown and described.

DESCRIPTION

FIG. 1 is a front and left side perspective view of a motor vehicle and/or toy vehicle replica showing our new design; FIG. 2 is a front and right side perspective view thereof; FIG. 3 is a front view thereof;

FIG. 4 is a rear view thereof;

FIG. 5 is a right side view thereof;

FIG. 6 is a left side view thereof; and,

FIG. 7 is a top view thereof.

The bottom view of the motor vehicle and/or toy vehicle replica forms no part of the claimed design.

1 Claim, 7 Drawing Sheets
